UNITED STATES PATENT OFFICE

91,144

DESIGN FOR AN EMBLEM

Stephen F. O'Shaughnessy, Derby, Conn.

Application September 28, 1933. Serial No. 49,363

Term of patent 7 years

To all whom it may concern:

Be it known that I, STEPHEN F. O'SHAUGHNESSY, a citizen of the United States, residing in Derby, in the county of New Haven and State of Connecticut, have invented a new, original, and ornamental Design for an Emblem, of which the following is a specification when taken in connection with the accompanying drawing:

Fig. 1 is a front elevation of an emblem showing my new design;

Fig. 2 is a side elevation of the same; and Fig. 3 is a section on line 3—3 of Fig. 1 showing the configuration of the outer surface.

I claim:

The ornamental design for an emblem substantially as shown.

STEPHEN F. O'SHAUGHNESSY.
